UNITED STATES PATENT OFFICE.

BENJAMIN W. TODD, OF SHERMAN, CALIFORNIA.

ARMATURE-BANDING MACHINE.

Application filed August 18, 1921. Serial No. 493,488.

To all whom it may concern:

Be it known that I, BENJAMIN W. TODD, a citizen of the United States, residing at Sherman, in the county of Los Angeles and State of California, have invented certain new and useful Improvements in Armature-Banding Machines, of which the following is a specification.

My invention relates to winding machines, 10 and more particularly to a machine especially adapted for winding the wire bands upon the armatures of electric motors and the like.

In winding bands of this character, it is 15 necessary that the wire be applied under a constant and even tension, in order to prevent unequal strains and consequent failure. It is also necessary to be able to back up the armature, and unwind the wire for a 20 considerable distance, without destroying the tension, in order to correct errors of direction, or for any other reason.

Therefore the objects of my invention are to provide a winding machine in which 25 the wire is kept under constant tension, and which may be reversed, to unwind a considerable length of wire, without destroying this tension. Further objects of the invention are to provide means for feeding the 30 wire, as it is used, from a reel, without allowing said reel to run ahead and cause slack, and to provide safety devices for guiding the wire so that, in the event of breakage under tension, the free end will not whip 35 back and injure the operator.

Although my invention is especially adapted for banding armatures, it is to be distinctly understood that it is not limited to such use. On the contrary, it may be used 40 with equal success for the winding of any wire or similar material upon a drum-like object, where constant tension is necessary or desirable. Moreover, although the machine embodying my invention is herein described and illustrated in its preferred form, 45 it is to be understood that changes, within the scope of the claims hereto appended, may be made in the form and construction of the machine without departing in any 50 degree from the spirit of the invention.

With this in view, a preferred embodiment of my invention will now be fully described with reference to the accompanying drawings, wherein:

55 Figure 1 is a front elevation of my com-

plete banding machine, the driving motor being omitted for the sake of clearness;

Fig. 2 is a plan view of the same, showing the driving motor;

Fig. 3 is an end elevation, viewed from 60 the right-hand end of Figs. 1 and 2;

Fig. 4 is a sectional detail, enlarged, of the tip of the wire guide;

Fig. 5 is an end view of the same, taken 65 on the line 5—5 of Fig. 4; and

Fig. 6 is a horizontal sectional detail, taken in the direction of the arrows on the line 6—6 of Fig. 1, certain parts being omitted for the sake of clearness.

In the drawings, the reference numeral 1 70 designates a bed, similar in general form and arrangement to the bed of an ordinary lathe. Said bed is provided with a fixed head-stock 2 and an adjustable tail-stock 3, the latter being formed in any suitable and 75 well known manner. Both head and tail-stocks are provided with centers 4 between which the armature A, indicated only in dotted lines in Fig. 1, may be swung for rotation.

The head-stock 2 has a spindle 5, Fig. 1, which is driven through worm gearing 6, preferably by an electric motor 7, Figs. 2 and 3. A friction clutch 8 and a brake 9 are interposed between the motor 7 and the 80 worm gearing 6, said brake comprising two adjacent friction disks, one carried by the worm gear housing 6', and the other by the 85 slideable clutch hub 8'. Said clutch hub 8' is moved longitudinally upon its shaft, to 90 operate the clutch and brake, by a bell-crank 10, Fig. 3, a vertical link 11, Figs. 1 and 3, and a treadle 12, the latter being pivotally supported at 13 and so arranged that pressure on said treadle engages the clutch and 95 disengages the brake. A spring 14, Fig. 3, normally holds the clutch out of engagement, and the brake members in frictional contact.

A face plate 15, Figs. 1 and 2, of the usual 100 well known form, and from which the armature may be driven by a suitable dog, indicated in dotted lines in Fig. 1, is rotatably mounted on the end of the spindle 5, and is driven by a jaw-clutch 16. Said jaw-clutch 105 is operated by a bell-crank 17, Fig. 1, a vertical link 18, and a treadle 19, the latter being pivotally supported at 20, Figs. 1 and 3, and so arranged that pressure on said treadle releases the jaw-clutch. A spring 21, Fig. 1, 110

normally holds said jaw-clutch in engagement.

Beneath the bed 1 of the machine is a horizontal fluid-pressure cylinder 22. A piston 23, Fig. 1, is slidable within said cylinder, and operates a piston rod 24, which carries a head 25, Figs. 1 and 6, upon which are mounted a pair of parallel pulleys 26, side by side, partially enclosed by a suitable 10 guard member 27. At the extreme left hand end of the bed is a fixed bracket 28, Figs. 1 and 2, upon which are mounted, side by side, two pulleys 29, in alignment with the pulleys 27. A third pulley 30 is also 15 mounted upon said bracket 28, slightly above the lower pair of pulleys 29.

The wire which is to be wound upon the armature is carried upon a reel 31, Figs. 1 and 2, removably mounted in bearing 20 brackets 32 at the extreme right-hand end of the bed 1. Said wire, as shown at 33, is led from said reel 31, over a guide pulley 34, Fig. 1, thence over one of the pulleys 29 carried by the fixed bracket 28, thence 25 back and over one of the pulleys 26 carried by the piston rod head 25, thence forwardly again over the other pulley 29 and back over the other pulley 26, and finally forwardly and over the upper pulley 30. The 30 piston-rod head 25 thus carries two bights of the wire 33, and the amount of slack which can be taken up by the movement of said rod is therefore equal to four times its own length.

From the rear of the bed 1 there extends a fixed semi-circular bracket 35, Fig. 2, which has a rearwardly projecting stud 36, Fig. 3, at its central portion. A vertical arm 37 is mounted on said stud for 40 swinging movement in a vertical plane parallel with the length of the bed, and has a counter-weight 38 to keep it normally upright. To the upper end of said arm 37 is pivoted a forwardly extending tube 39, the latter being capable of swinging, upon said arm, in a vertical plane at right angles to the plane of movement of said arm. The wire 33, after leaving the last take-up pulley 30, passes over guide 45 pulleys 40 and 41 carried by the bed and the bracket 35 respectively, as shown in Fig. 2, thence over a pulley 42, Fig. 3, mounted at the lower end of the swinging arm 37, thence up and over a pulley 43 at the upper 50 end of said arm, and finally forwardly through the tube 39. Said tube follows the wire freely to any portion of the armature upon which it is being wound, the vertical movement of the forward end of said tube 55 permitting it to be wound upon armatures of any diameter capable of being swung in the machine, and the horizontal movement of the entire tube enabling it to travel to any position between the centers 4.

65 The forward end of the guide tube 39

is provided with a cap 44, Figs. 4 and 5, within which are a pair of complementary sliding jaws 45, adapted for limited sliding movement within said cap, and normally held in their retracted or rear position by 70 a spring 46, Fig. 4, surrounding said jaws and within said cap, said spring acting between the forward end 47 of the cap and rear flanges 48 formed upon the jaws. The forward portions of the said jaws normally 75 fit freely within a circular orifice in the end 47 of the cap, and back of said forward portions the jaws are exteriorly relieved, as shown at 49. A passage 50 is formed between said jaws. The diameter of said passage at its forward portion is only very 80 slightly larger than the diameter of the wire, but considerably larger at its rear portion, there being a slightly inclined interior shoulder formed at 51 in said passage. 85

When there comes a splice or joint in the wire (not shown in Fig. 4), said splice, striking the interior shoulder 51, moves the jaws 45 outwardly until their relieved portions 49 clear the end 47 of the cap 44, whereupon said jaws separate sufficiently to allow the splice to pass through. The spring 46 then returns the jaws to their normal position. The wire thus has a guide which fits it at 90 all times sufficiently closely to prevent chattering, but which will allow splices or joints to pass through. The interior passage between the jaws 45 must conform to the size and cross-sectional form of the wire being used, said jaws being easily replaced by unscrewing the cap 44 from the end of the tube 39.

The reel 31 is provided at one side with a brake drum 52, Figs. 1, 2 and 3, about which is positioned a brake band 53. One end of 105 said band is anchored to a fixed bracket 54, Fig. 1, and the other end is movable upon a fixed rod 55 extending from said bracket. A nut 56 is provided upon said rod for adjusting the band 53, and cushioning springs 57 are positioned on each side of the free end of said band. 110

An arm 58 is connected with said free end of the band 53, and is connected through a cushioning spring 58' and a pushrod 59, 115 with a lever 60, the latter being pivoted at 61 and having its lower end connected with a longitudinal horizontal rod 62, which extends the entire length of the machine beneath the bed 1, and is parallel with the piston rod 24. A guide 63, Figs. 1 and 6, supports the forward end of the rod 62, and a collar 64, Fig. 6, is fixed upon said rod. Said collar is positioned to be engaged through a cushioning spring 64' by an arm 120 65 extending laterally from the piston rod head 25, and freely slidably upon said rod 62, so that, when the piston rod 24 approaches the left-hand, or outer end of its travel, as shown in Fig. 6, it moves the rod 125 66

62 to the left, thereby releasing the brake band 53. The springs 57 returns said band to its normal tension as soon as the piston rod 24 moves in again sufficiently to cause 5 its arm 65 to free the collar 64.

In the operation of the machine, fluid, preferably air, under pressure, is admitted to the cylinder 22 through a connection 66, Fig. 1, at its left-hand end, thereby forcing 10 the piston 23 and its rod 24 in to the right-hand limit of its travel. The brake-band 53 is then adjusted, by means of the nut 56, so tightly that the desired normal tension on the wire 33 will not cause the reel 31 to 15 revolve. Winding is then commenced, and, as it proceeds, the piston 23 is drawn out, against the air pressure in the cylinder 22, until it approaches the outer or left hand end of its stroke, when the release rod 62 20 is moved by the contact of the arm 65 with the collar 64, thereby releasing the brake band 53 and allowing the reel 31 to revolve. When enough wire has been unwound from 25 said reel to allow the piston rod 24 to return sufficiently to free the release rod 62, the brake band 53 again holds said reel stationary and the piston rod 24 begins to be drawn out again.

Thus a condition of virtual balance is 30 maintained, the piston rod 24 moving back and forth only a slight amount, near the outer limit of its possible travel, and the brake band 53 alternately releasing and holding the reel 31. The tension on the wire 35 is therefore constant at all times, being dependent solely upon the pressure of the air supplied to the cylinder 22. The reel 31, being controlled by its brake band 53, pays out the wire only as it is used, and is never 40 allowed to run ahead and cause slack in said wire.

If it is necessary to back up the armature, on account of over-lapping or unequal spacing of the wire, or for any other reason, the 45 reel is held stationary by its brake band 53, and the air pressure in the cylinder 62 causes the piston rod 24 to take up the slack as the wire is unwound from the armature, without lessening its tension. In actual practice, for 50 example, in a machine having an air cylinder four feet long, sixteen feet of wire could be backed off the armature without lessening the normal tension. Such backing and un-winding is preferably done by releasing the 55 jaw-clutch 16, by pressure on the treadle 19, thus freeing the armature A from its driving mechanism, and allowing it to be turned backwardly, by hand, the necessary amount.

The machine is at all times under the instant control of the operator, who stands 60 behind the bed 1, in a position convenient to the treadles 12 and 19. The driving motor 7 preferably runs continuously, the machine being started and stopped by means of the 65 friction clutch 8 and the brake 9, operated by

the treadle 12. Release of said treadle instantly stops the machine, by disengaging said clutch and applying said brake.

In this position also the operator is well 70 out of the way of the wire, and therefore not liable to injury in case of breakage, the guide tube 39 protecting him in the event of breakage near the armature.

I claim:—

1. A banding machine comprising means 75 for rotating the object to be banded; a cylinder; a piston operable therein by fluid under pressure; a rod connected with and moved by said piston; a pair of pulleys carried by said rod; a second pair of pulleys mounted 80 upon a fixed axis and aligned with the first pair, said pulleys being adapted to receive a double bight of the banding material; and means controlled by the movement of said piston for feeding the banding material to 85 said pulleys.

2. A banding machine comprising means for rotating the object to be banded; means for feeding the banding material thereto under tension; and guide means for said banding material comprising an upright member 90 adapted to swing in a direction parallel with the axis of said object, and a tubular member associated with said upright member and adapted for swinging movement in a direction 95 perpendicular to the axis of said object.

3. A banding machine comprising means for rotating the object to be banded; means for feeding the banding material thereto under tension; and means for guiding said banding material comprising a tubular member adapted for both vertical and horizontal movement, and a pair of complementary jaws mounted in the end of said tubular member said jaws having a channel 100 formed between them through which the banding material may pass in close fitting relation, and said jaws being capable of separation to permit the passage of enlargements in said banding material. 105

4. A banding machine comprising means for rotating the object to be banded; means for feeding the banding material thereto under tension; and means for guiding said banding material comprising a tubular member adapted for both vertical and horizontal movement, a pair of separable and longitudinally slidable jaws mounted in the end of said tubular member, said jaws having a channel 110 formed between them through which the banding material may pass in close fitting relation, and said jaws being capable of separation to permit the passage of enlargements in said banding material, only 115 when moved longitudinally out of their normal position, and a spring for retaining said jaws in said normal position. 120

In testimony whereof I have signed my name to this specification.

BENJAMIN W. TODD.
